UNITED STATES PATENT OFFICE

167,564

CANDY CONFECTION

Josephine Q. Dunbar, Kansas City, Kans.

Application April 18, 1952, Serial No. 19,390

Term of patent 7 years

(Cl. D82—2)

To all whom it may concern:

Be it known that I, Josephine Q. Dunbar, a citizen of the United States, residing at Kansas City, State of Kansas, have invented a new, original, and ornamental Design for a Candy Confection, of which the following is a specification, reference being had to the accompanying drawing, forming a part hereof.

Fig. 1 of the drawing is a top plan view of a candy confection, embodying my design and

Fig. 2 is a perspective view thereof.

I claim:

The ornamental design for a candy confection, substantially as shown.

JOSEPHINE Q. DUNBAR.
